UNITED STATES PATENT OFFICE.

THOMAS W. LANE, OF BOSTON, ASSIGNOR TO HIMSELF AND CHARLES WILLIAMS, JR., OF SOMERVILLE, MASSACHUSETTS.

TELEPHONE SWITCH-BOARD.

SPECIFICATION forming part of Letters Patent No. 244,625, dated July 19, 1881.

Application filed May 16, 1881. (No model.)

To all whom it may concern:

Be it known that I, THOMAS W. LANE, of Boston, in the county of Suffolk and State of Massachusetts, have invented certain Improvements in Telephone Switch-Boards, of which the following is a specification.

This invention relates to switch-boards having a series of parallel metallic strips, each connected to a different line-circuit, a series of connecting-strips at right angles to the line-circuit strips, and devices for connecting any two of the line-circuit strips through the medium of the connecting-strips.

The invention consists, as a whole, in a switch-board embodying the following elements: First, a series of line-circuit strips, each adapted to be turned laterally to separate it from a ground-strip, against which it is normally held with a yielding pressure; secondly, a series of connecting-strips, each provided with as many plugs or connecting devices as there are line-circuit strips, said plugs being permanently secured to the connecting-strips and normally disconnected from the line-circuit strips, and adapted to make contact with the line-circuit strips, and at the same time to engage with and hold said strips from the ground-strip; and, thirdly, means for disengaging the line-circuit strips from the plugs of the connecting-strips and permitting said plugs and strips to automatically resume their normal positions.

The object of the invention is to enable the connections between the line-circuit and connecting strips to be made and broken at a central office with the utmost facility, and to enable a single operator to attend to a greater number of circuits than in switch-boards of this class heretofore made in which a single plug or connecting device, movable from one connecting-strip to another, is employed for each line-circuit strip.

Of the accompanying drawings, forming part of this specification, Figure 1 represents a top-plan view of a switch-board embodying my invention. Figs. 2 and 3 respectively represent sections on the lines *x x* and *y y*, Fig. 1.

The same letters relate to the same parts in all the figures.

50 In the drawings, B represents a switch-board

having a series of line-circuit strips, *a*, and a ground-strip, *c*, common to all the line-circuit strips. The strips *a* are adapted to be moved so that they can be separated from the ground-strip, and are normally held in contact with said strip with a yielding pressure. In the present instance said adaptation is effected by pivoting the strips *a* at their ends on screws *b*, passing through the frame of the switch-board, and the yielding pressure is effected by springs *s*, attached to the strips and to pins secured in the frame.

The connecting-strips *d* are, as usual, arranged at right angles to the line-circuit strips, and are insulated therefrom by the frame of the switch-board to which they are rigidly attached. Each strip *d* has a series of plugs or connecting devices, *e*, there being as many of said plugs in each strip *d* as there are line-circuit strips. These plugs are movable longitudinally toward and from the line-circuit strips, and are normally held away from said strips by springs *f*, but are adapted to be forced inwardly against the pressure of said springs to make contact with the line-circuit strips, as hereinafter described. Each plug *e* has a notch or recess, *n*, formed in the lower portion of its shank, and a shoulder or projection, *h*, on the lower end of the plug, the under side of said shoulder being rounded off and adapted to come in contact with a line-circuit strip, *a*, when the plug is forced inwardly through the orifice in the strip *d*, the pressure of the plug causing the strip *a* to be moved laterally or partially rotated upon its pivots, and breaking its contact with the ground-strip. When the inward movement of the plug *e* is sufficient to bring the shoulder *h* below the lower edge of the line-circuit strip the latter is caused by its spring to engage with said shoulder, as shown in Fig. 2, and the plug and strip are thus interlocked and mutually held in contact with each other, so that neither can resume its normal position, the line-circuit strip being disconnected from the ground-strip.

The general operation connecting the line-circuits with the switch-board is effected in the usual manner—that is to say, whenever a subscriber on one of the line-circuits (say No. 4) desires to communicate with another sub-

scriber, (say No. 1,) the plugs of any unoccupied connecting-strip corresponding to said line-circuit strips are pushed inwardly and engaged with the specified line-circuit strips, 5 as already described, and as shown in Fig. 2, said strips being thereby disconnected from the ground-strip, as shown in Fig. 3, so that subscribers on the two circuits can communicate.

10 It is, of course, necessary to provide means for disengaging the plugs from the line-circuit strips, and allowing each to automatically resume its normal position. To this end I provide, in the present instance, a series of spring-retracted plugs or plungers, *p*, located on a strip, *i*, attached to the frame of the switch-board, and provided with rounded inner ends, without shoulders, adapted, when pressed against the line-circuit strips, to swing said 15 strips outwardly until they are disconnected from the shoulders of the plugs *e*, the latter being forced outwardly by their springs, and the line-circuit strips being brought by their springs into contact with the ground-strip as 20 soon as the plugs *p* are released by the operator. The outward movement of the plugs is limited by a pin, *t*, passing transversely through the shank of the plug below the strip *d*.

It will be seen that by the described improvements much time is saved in making and breaking connections as compared with a board in which a plug has to be moved from strip to strip, as heretofore, the operator being enabled to make and break the connections by a single 30 rapid pressure on the spring-plugs. An operator can therefore attend to a much larger number of circuits than has been possible heretofore.

Having thus described my invention, I claim—

1. In a switch-board of the class described, the combination of the line-circuit strips, each normally held in contact with a ground-strip, and adapted to be separated from the latter, and the connecting-strips, each having as many 40 spring-retracted plugs or connecting devices as there are line-circuit strips, said plugs being normally disconnected from the line-circuit strips, and adapted to be engaged with and hold the latter when they are separated from 45 the ground-strip, as set forth.

2. In a switch-board of the class described, the combination of a series of line-circuit strips, pivoted at their ends, and held normally by 50 springs against a ground-strip, a series of connecting-strips, each provided with as many 55 spring-plugs or connecting devices *e* as there are line-circuit strips, each plug or connecting device being adapted by a single movement to separate from the ground-strip one of the line-circuit strips, to hold the latter so separated, and to connect it to the connecting-strip to which the plug belongs, and a series of releasing devices or plungers adapted to disengage 60 the plugs *e* from the line-circuit strips and 65 permit each to resume its normal position, as set forth.

In testimony whereof I have signed my name to this specification in the presence of two subscribing witnesses.

THOMAS W. LANE.
